UNITED STATES PATENT OFFICE.

HENRI GUYOT, OF LA SOUTERRAINE, FRANCE.

DOUBLE STAMP-HAMMER.

SPECIFICATION forming part of Letters Patent No. 651,754, dated June 12, 1900.

Application filed December 15, 1899. Serial No. 740,430. (No model.)

To all whom it may concern:

Be it known that I, HENRI GUYOT, a citizen of the Republic of France, residing at La Souterraine, department of Creuse, France, 5 have invented new and useful Improvements in Double Stamp-Hammers, of which the following is a specification.

My invention relates to double stamp-hammers formed of a base *a*, the upper surface 10 of which is provided with two grooves *b* for receiving steel blocks serving as anvils. The base *a* supports a horseshoe-shaped armature *c*, which supports the upper part of the machine.

15 In the accompanying drawings, Figure 1 is a front elevational view of my construction. Fig. 2 is a side view thereof, showing the armature which supports the upper structure. Figs. 3, 4, and 5 are views of details of my 20 construction, showing more particularly how the two eccentrics are simultaneously operated by one pulley.

The upper part of my construction comprises two uprights *d* and *d'*, which at their 25 tops form two arms, so as to embrace three pulleys, of which the two lateral, *e* and *e'*, are fixed pulleys, while the central pulley *f* is loose. Each of the fixed pulleys has for its object to operate an eccentric *g* or *g'*, or, by 30 means of a peculiar system of keying, one of these fixed pulleys can be made to operate simultaneously the two eccentrics. This arrangement will be described hereinafter. A rod *h* *h'* is linked, respectively, to each of 35 the eccentrics *g* *g'*. These rods can be regulated as to their length, and their ends are each provided with a spring in order to increase the force of the fall of the corresponding hammers *i* or *i'*. The hammers *i* *i'* are 40 guided by triangular guide-rods *j*, fixed to the uprights *d* *d'* and to two uprights *d* *d'*, fixed to the former by cross-beams *k*. Said hammers *i* *i'* are located in the same vertical 45 plane as the grooves *b* of the base *a*, in which the anvils are received, as above stated.

The peculiar mechanism for actuating simultaneously the two eccentrics by one pulley only works as follows, Figs. 3, 4, and 5: The driving-shaft which carries the pulleys 50 is made of two parts, one solid *l* and one hollow part *l'*, into which the solid part fits.

The outside surfaces of both the male and female parts *l* and *l'* are provided with a groove wherein a key *n* can engage in order to make both parts of the shaft solidary the 55 one with the other. In order to facilitate the displacement of the key either for engaging or disengaging the two parts of the shaft, said key *n* is fixed to a ring *o*, movable in the desired direction by means of a lever *p*, oscillating at the point *p'*, Fig. 1, operated by hand by means of a rod *g* and a lever *g'*.

The displacement of the belt-shifting fork *r* is effected by means of a sliding rod *r'*, actuated from right to left, and vice versa, by 60 means of an elbowed lever *s*, a rod *s'*, and a lever *t*.

Considering the belt arrangement for engaging and disengaging the same, it will be possible to make either of the pulleys turn 70 at will, and thus to bring into action either of the hammers, and by means of the key *n* it will be possible to have both hammers operating simultaneously, no matter upon which of the fixed pulleys the belt be placed.

Having now described my invention, what I claim is—

1. The combination with two hammers, of a standard common to both, two operating crank-shafts, one for each hammer, said 80 shafts being in line with each other, a source of power adjacent to both shafts, and means for connecting it with either one of said shafts at will.

2. The combination with two hammers, of 85 a standard common to both, two operating crank-shafts, one for each hammer, said shafts being in line with each other, a fixed pulley on each shaft, a loose pulley between said fixed pulleys, and means for shifting a 90 belt from said loose pulley to either one of the fixed pulleys at will.

3. The combination with two hammers, of a standard common to both, two operating crank-shafts, one for each hammer, said 95 shafts being in line with each other, means for rotating one of said shafts, and means for locking said shafts together as one.

4. The combination with two hammers, of a standard common to both, two operating 100 crank-shafts therefor arranged in line with each other, means for rotating one of said

shafts, a keyway in each shaft, a key in one of said keyways, and means for engaging said key with the other keyway to lock the two shafts together as one.

5. The combination with two hammers, of a standard common to both, two operating crank-shafts therefor arranged in line with each other, means for rotating one of said shafts, a keyway in each shaft, a key in one of said keyways, a collar on said shaft at-

tached to said key, an elbow-lever engaging said collar, and means for operating said lever.

In testimony that I claim the foregoing I have hereunto set my hand this 15th day of November, 1899.

HENRI GUYOT.
